UNITED STATES PATENT OFFICE.

CHARLES A. ROOS, OF CINCINNATI, OHIO, ASSIGNOR OF ONE-HALF TO GEORGE W. MEYER, OF CINCINNATI, OHIO.

ADJUSTABLE SHORE.

Application filed June 30, 1922. Serial No. 572,042.

To all whom it may concern:

Be it known that I, CHARLES A. Roos, a citizen of the United States, residing at Cincinnati, in the county of Hamilton and 5 State of Ohio, have invented new and useful Improvements in Adjustable Shores, of which the following is a specification.

My invention relates to adjustable shores or extensible uprights, used briefly in the 10 building art to support forms for concrete, or anywhere where a temporary support is required. My invention includes a metal channel adapted to stiffen each of the main supporting members, which are usually 15 made of wood.

Another object of my invention is use of a cross-head and as the cross-head works in the channel it does not protrude beyond the sides of the supports, therefore, the shores 20 may be stacked one upon another rapidly and without damage to each other, and occupy the least possible space. Nor will tie straps interfere with the full extension of the shore. Should the main supporting 25 members warp somewhat, the cross-head will still work freely in the channels; and tie straps may be used to prevent warping and to keep the supports in their correct relative 30 positions even when supporting great weights.

My invention is illustrated in the accompanying drawings of which:—

Figure 1, a front elevation, shows my improved shore (shortened by breaking), in 35 partly extended position.

Figure 2, a side elevation, shows my improved shore (similarly broken) in the same position, and

Figure 3 is a cross section on the line 3—3 40 of Figure 1.

Referring now to the drawings.

The co-ordinating elements are designated respectively as A and B; the part A being vertically adjustable upon and telescopically engaged with the part B. The 45 adjustable part A comprises a pair of stanchions or main supporting members, a^1 and a^2 , preferably of wood, spaced apart in parallel relation by tie straps a^3 rigidly connected to and preferably sunk into said stanchions. A pair of channel guide elements a^4 preferably of sheet metal and co-extensive with the effective length of the 50 stanchion members a^1 and a^2 , are secured one 55 to the inner side of each of said stanchion

members. The relatively fixed or base element B, preferably made of iron or steel pipe, is provided with a cross head pin b^1 at its upper end. Said cross head pin projects laterally into the channel of both the 60 channel shaped elements a^4 to slide therein and be guided thereby, when the part A is being adjusted.

The part A at the top has a tie beam a and the part B at the bottom is provided 65 with a terminal foot b of somewhat enlarged area.

A plate a^5 is bored through its center and secured to the bottom of the stanchions a^1 and a^2 . 70

An automatic lock is provided to hold the elements in position after adjustment. Said lock consists of a perforated plate C having upturned edge c suspended at one side upon a pivot c^2 extending thru the stanchions a^1 75 and a^2 and the upturned sides c of the plate C.

A pin c^3 is secured to the plate C and holds in position a spring E, forcing the front edge c^1 of the plate C upward, making the diagonally opposite edges of the plate C bite into and grip the element B thereby holding the elements in locked relation to each other. In order to release the lock it will only be necessary to bear down 80 on the front c^1 of the plate C, bringing it to a horizontal position. Obviously more than one such locking plate may be used if desired.

Many changes may be made in my device 85 without departing from the spirit of the invention; as for instance, the cross head may be made with vertical tongue or groove on the faces opposite the supports and the supports with groove or tongue respectively 90 adapted to laterally engage the cross head being guided thereby.

Having described my invention, I claim 95 as my invention and desire to secure by Letters Patent of the United States:—

1. An adjustable shoring device having in combination an extensible member formed of parallel bars secured in spaced relation to each other, longitudinal metal guides on the inner sides of said parallel bars, a relatively fixed member telescopically adjustable within the extensible member, having a cross head lying wholly within the enclosure formed by said bars and adapted to engage said metal guides, and 105 110

means for locking said extensible and relatively fixed members in adjusted relation to each other.

2. In combination with an adjustable shoring device comprising two extensible bars held in parallel spaced relation by a series of rigid spacing bars, and telescopically engaged with a relatively fixed member having a cross head lying wholly within

the space formed by said extensible bars and 10 spacing bars and a channel shaped element adapted to co-act with said cross head, secured to the inner side of each of said extensible bars.

In testimony whereof I have hereunto set 15 my hand.

CHARLES A. ROOS
